UNITED STATES PATENT OFFICE.

SIMON LINZ, OF DALLAS, TEXAS.

DESIGN FOR A CUP.

SPECIFICATION forming part of Design No. 35,942, dated June 10, 1902.

Application filed May 10, 1902. Serial No. 106,843. Term of patent 7 years.

To all whom it may concern:

Be it known that I, SIMON LINZ, a citizen of the United States, residing in the city of Dallas, in the county of Dallas and State of Texas, have invented and produced a new and original Design for a Cup; and I do hereby declare the following to be a full, clear, and exact description of the same, reference being had to the accompanying drawings, forming a part thereof.

Figure 1 in the drawings is a perspective view of a cup, showing a portion of my design applied thereto. Fig. 2 is a similar view of the same, showing another portion of my design. Fig. 3 is also a similar view showing the third portion of my design; and Fig. 4 is also a perspective view of a cup, showing the remaining portion of my design.

The leading feature of the design consists of the representation substantially as shown in the accompanying drawings.

Referring to the drawings, 1 indicates a cup formed with a band 2 at the top and a band 3 at the bottom, the band at the bottom having an annular rib or bead 4 running through the same.

The design is formed in panels arranged circumferentially of the cup, each panel being separated from the other by a border of fanciful contour, the different parts of each panel also being separated in a similar manner. The panel shown in Fig. 1 contains the Con-

federate Monument, as at 5. In the second panel (shown in Fig. 2) is a representation of the Linz Building, as at 6, at the top, the lower part of the panel containing the representation of a steer's head, as at 7. The third panel (contained in Fig. 3) shows a representation, in the lower part of the panel, of the Court-House at Dallas, as at 8. Above this building is a representation of a bale of cotton, as at 9. The fourth panel, as shown in Fig. 4, contains a representation of the Dallas Public Library, as at 10, in the upper half of the panel, the lower half comprising a wreath, as at 11, partly surrounding a five-pointed star, as at 12. All the figures of the different panels, as well as the fanciful border separating the same, are arranged in bas-relief. Words descriptive of each object represented in the design will appear in the finished product.

Having now described my invention, what I claim as new, and desire to secure by Letters Patent, is—

The design for a cup, substantially as herein shown and described.

In testimony whereof I hereunto affix my signature in presence of two witnesses.

SIMON LINZ.
